UNITED STATES PATENT OFFICE.

JAMES S. KNIGHT, OF PORTLAND, MAINE.

DESIGN FOR A CAN.

SPECIFICATION forming part of Design No. 33,704, dated December 11, 1900.

Application filed November 15, 1900. Serial No. 36,646. Term of patent 7 years.

To all whom it may concern:

- Be it known that I, JAMES S. KNIGHT, a citizen of the United States, and a resident of Portland, in the county of Cumberland and State of Maine, have invented and produced 5 a new and original Design for Cans, of which the following is a specification, reference being had to the accompanying drawings, forming a part thereof.
- 10 In said drawings, Figure 1 is an elevation of a can, showing my new design. Fig. 2 is a sectional view of the same, taken on lines xx of Fig. 3; and Fig. 3 is a top view of a can embodying my new design.
- 15 As shown in the drawings, the leading or material feature of my design consists of a can having a bottom A, gradually-sloping wall B, a vertical wall C, a cover D, and han-

dle E, said wall B gradually sloping from the bottom A to the vertical wall C, the distance from side to side of the wall B being less where it joins vertical wall C than where it joins the bottom A. 20

Having thus described my invention, what I claim as new, and desire to secure by Letters 25 Patent, is—

The design for a can as herein shown and described.

In testimony whereof I affix my signature, in presence of two witnesses, this 13th day 30 of November, 1900.

JAMES S. KNIGHT.

Witnesses:

NATHAN CLIFFORD,
ELGIN C. VERRILL.
